Specification for Design.

Patented May 13, 1919.

Application filed May 13, 1918. Serial No. 234,331. Term of patent 7 years.

To all whom it may concern:

Be it known that we, HAROLD EDWARD NOCK and GEORGE F. PARKER, citizens of the United States, residing at Newburyport, in the county of Essex and State of Massachusetts, have invented a new, original, and ornamental Design for a Tray, Dish, Plate, Platter, Bowl, Compote, Basket, or Analogous Article of Hollow Ware, of which the following is a specification, reference being had to the accompanying drawing, forming a part thereof.

In the accompanying drawing Figure 1 is a plan view of our design shown embodied in a meat tray, and Fig. 2 is a section on the line 2—2 of Fig. 1.

Copies of this patent may be obtained for five cents each, by addressing the "Commissioner of Patents, Washington, D. C."

The design comprises an ornamental design having the configuration and characteristics delineated and, as shown, is embodied in a meat tray, but it is contemplated that the design may also be embodied in, or applied to, dishes, plates, platters, bowls, compotes, baskets and other analogous articles of hollow ware.

We claim:

The ornamental design for a tray, dish, plate, platter, bowl, compote, basket or analogous article of hollow ware, as shown and described.

HAROLD EDWARD NOCK.
GEORGE F. PARKER.
